UNITED STATES PATENT OFFICE.

EDWIN R. CAHOONE, OF TROY, NEW YORK.

GRATE.

No. 926,095.

Specification of Letters Patent.

Patented June 29, 1909.

Application filed November 20, 1905. Serial No. 288,302.

To all whom it may concern:

Be it known that I, EDWIN R. CAHOONE, a citizen of the United States, residing at Troy, in the county of Rensselaer and State of New York, have invented new and useful Improvements in Grates, of which the following is a specification.

This invention relates to improvements in grates.

10 My present improvement pertains more particularly to grates used in stoves which burn soft coal, or lignite. When burning this class of fuel, it is of the utmost importance that the grate be practically closed to prevent the fuel falling into the ash pan below, and yet admit sufficient draft or circulation of air to the fire pot to assist the combustion.

To this end my invention comprehends 20 providing a lower stationary grid, and an upper movable grid the under side of which may be cross grooved, the two grids being so related that when the grate is closed to prevent the fuel falling from the fire pot, 25 air is admitted, yet the relation of parts does not prevent the reciprocating of the movable grid to bring the openings into register to allow the ashes etc. to fall to the ash pan.

30 A further object of the invention is to provide in a reciprocating grate having the above noted characteristics, depressions to receive ashes to prevent the heat destroying the metal, the movable grid assisting in 35 packing the ashes in the depressions of the stationary grid.

Other objects and advantages will be hereinafter referred to and particularly pointed out in the claims.

40 In the drawing Figure 1 is a perspective view of my improved grate. Fig. 2 is a central section of the same, showing the lower grid openings substantially closed. Fig. 3 is a similar view, showing the movable grid moved to bring its openings in 45 register with the openings of the lower grid.

The numeral 1 represents the stationary grid, 2 the bars, and 3 the spaces between the bars. Bars 2 are for lightness made 50 convex on their lower sides, while in their upper sides they are formed with depressions 4, which receive ashes to protect the metal.

55 The movable grid 5 is mounted on the stationary grid 1, and consists of a series of bars 6, with intervening spaces 7; the bars

6 and spaces 7 being the same in number as bars and spaces 2 and 3 of the stationary grid. The bottoms of the bars 6 are flat as at 8, and their edges are beveled as at 9, the distance between the lower beveled edges 10 of the bars 6 being slightly less than the spaces 3, while the distance between the upper edges 10^a of the beveled sides is greater than the said spaces 3, to form overhanging 65 portions, as shown in Fig. 2. The upper part of bars 6 are formed with depressions 12, to receive ashes, for various reasons.

For convenience of illustration, I have shown the stationary grid provided with a 70 surrounding flange 13, and the movable grid with a handle 14, however, these minor features may be altered without departing from the spirit and scope of my invention.

When burning soft fuel, fire is made on 75 the grate, where the parts are in the position shown in Fig. 2, ashes being supported in the depressions 4 and 12, and air passing through the passages 15 formed adjacent the beveled edges 9, and between the bars 2 and 80 6. This construction prevents the fine fuel falling from the grate and at the same time permits the admission of air to the fire pot to promote combustion. Air passes freely through the passages 15 in opposite directions and is distributed to the mass of fuel 85 which produces a uniform grade of combustion. The air striking the beveled sides of the bars is deflected into the fire and said air also serves to keep the bars cool. When 90 shaking the grate, the movable grid is reciprocated over the surface of the stationary grid and in so doing, the ashes in the depressions 4 soon become packed, and the surplus is forced through the openings 3 and fall to 95 the ash pan below. Obviously continued shaking of the movable grid, jars the ashes above the registering openings, and they fall to the ash pan below. The depressions receive a sufficient quantity of ashes to materially 100 protect the metal from the heat and the arrangement of the two grids insures a proper supply of air being delivered to the fuel.

I may provide grooves 15, in the edges of 105 the bars of the upper grid for the passage of air when ashes accumulate on the base of the lower grid.

What I claim is:

1. A grate comprising a stationary grid 110 formed with spaced bars, a movable grid superposed on the stationary grid and

formed with spaced bars with sides inclined inwardly from the top to the bottom and grooves along the overhanging edges, the upper ends of the spaces between the bars of the movable grid being narrower than the width of the bars of the stationary grid, and the lower ends of said spaces being wider than the bars of the stationary grid, whereby when the grate is closed the upper edges of the bars of the movable grid will overhang the bars of the stationary grid, and the lower edges of the bars of said movable grid will be spaced from the upper edges of the bars of the stationary grid.

2. A grate comprising a stationary grid formed with spaced bars, and a movable grid superposed on the stationary grid and formed with spaced bars having their edges beveled inwardly from the top to the bottom, the upper ends of the beveled spaces between the bars of the movable grid being narrower than the width of the bars of the stationary grid and the lower ends of said beveled spaces being wider than the width of the bars of the stationary grid, and the upper faces of the bars of the movable grid being wider than the spaces between the bars of the movable grid whereby when the grate is closed air passages will be formed between the lower edges of the bars of the movable grid and the upper edges of the bars of the stationary grid, and the edges of the bars of the movable grid will overhang the bars of the stationary grid.

3. A grate comprising a stationary grid formed with spaced bars provided with depressions for the reception of ashes, and a movable grid superposed on the stationary grid and formed with spaced cross-bars provided with depressions to receive ashes and having sides inclined inwardly from top to bottom, the upper ends of the spaces between the bars of the movable grid being narrower than the width of the bars of the movable grid, the lower ends of said spaces being wider than the width of the bars of the stationary grid, whereby when the grate is closed the upper edges of the bars of the movable grid will overhang the bars of the stationary grid, and the upper edges of the bars of the stationary grid will be spaced from the lower edges of the bars of the movable grid.

4. A grate comprising a stationary grid formed with spaced cross-bars provided on top with depressions, and a movable grid superposed on the stationary grid and formed with spaced cross-bars having their edges beveled inwardly from the top to the bottom and their bottoms flat, the flat bottoms of the bars of the movable grid being on a plane with the upper edges of the bars of the movable grid adjacent the depressions therein, the upper ends of the spaces between the bars of the movable grid being narrower

than the width of the bars of the stationary grid, and the lower ends of said spaces being wider than the width of the bars of the stationary grid, whereby when the grate is closed the upper edges of the bars of the movable grid will overhang the bars of the stationary grid, and the upper edges of the bars of said stationary grid will be spaced from the lower edges of the bars of the movable grid.

5. A grate comprising a movable grid formed with spaced cross-bars with their sides inclined downwardly and inwardly and having grooves in the sides and depressions in their upper surfaces to receive ashes, a stationary grid having spaced cross-bars with depressions to receive ashes, the movable grid being superposed on the stationary grid, the upper edges of the bars of the movable grid overhanging the bars of the stationary grid when the grate is in closed position and the spaces between the bars of the movable grid being wider at their lower edges than the bars of the stationary grid, whereby when the grate is closed spaces will be formed between the lower edges of the bars of the movable grid and the edges of the bars of the stationary grid.

6. A grate comprising a movable grid having spaced cross-bars with their sides inclined downwardly and inwardly and formed with grooves in their side edges, and a stationary grid formed with spaced cross-bars, the movable grid being superposed on the stationary grid, the upper edges of the bars of the movable grid overhanging the bars of the stationary grid when the grate is in closed position and the lower ends of the spaces of the movable grid being wider than the width of the bars of the stationary grid, whereby when the grate is closed the lower edges of the bars of the movable grid will be spaced from the upper edges of the bars of the lower grid to form air passages.

7. A grate comprising a movable grid having cross-bars formed with depressions to receive ashes and having sides inclined inwardly from the top downwardly, a stationary grid having cross-bars, the movable grid being superposed on the stationary grid, the upper edges of the bars of the movable grid overhanging the bars of the stationary grid when the grate is in closed position and the spaces at the top of the movable grid between the cross-bars thereof being narrower than at the bottom of said bars, and the bars of the stationary grid being narrower than the lower ends of the spaces of the movable grid, whereby when the grate is closed the top edges of the bars of the stationary grid will be spaced from the lower edges of the bottoms of the bars of the movable grid.

8. A grate comprising a grid having

spaced cross-bars, a second grid having spaced cross-bars, one stationary and the other being reciprocatingly mounted thereon, the bottom of the spaces between the bars of the second mentioned grid being wider than the upper edge of the cross-bars of the first-mentioned grid, the upper edges of the bars of the upper grid overhanging the bars of the stationary grid when the 5 grate is in closed position and the lower edges of the bars of the movable grid spaced from the bars of the stationary grid whereby when the grate is closed air passages are formed each side the bars of the first mentioned grid, the upper faces of both grids being formed with depressions.

9. A grate comprising two grids one

superimposed upon and movable with relation to the other, each grid being formed of spaced bars, those of the movable grid 20 having inwardly inclined sides with their upper edges overhanging the bars of the stationary grid when the grate is in closed position, the lower edges of the bars of the movable grid being spaced from the bars of the stationary grid whereby when the grate is closed 25 passages are provided for the air adjacent the inclined sides of the upper grid.

In testimony whereof I affix my signature, in presence of two subscribing witnesses.

EDWIN R. CAHOONE.
